HENRY B. COOLEY, OF KENSINGTON, CONNECTICUT, ASSIGNOR TO THE AMERICAN PAPER GOODS COMPANY, OF MONTCLAIR, NEW JERSEY, A CORPORATION OF NEW JERSEY.

DRINKING-CUP.

REISSUED

1,148,149.

Specification of Letters Patent.

Patented July 27, 1915.

Application filed April 4, 1914. Serial No. 829,488.

To all whom it may concern:

Be it known that I, HENRY B. COOLEY, a citizen of the United States, residing at Kensington, in the county of Hartford, 5 State of Connecticut, have invented a new and Improved Drinking-Cup, of which the following is a specification.

My invention relates more especially to that class of drinking cups that are made 10 from paper or other light material and that are intended for individual use, and an object of my invention, among others, is to provide a cup of this class with its lip thickened to provide sufficient rigidity to resist 15 collapse under weight of the contents.

One form of cup embodying my invention, and in the construction and use of which the objects herein set out, as well as others, may be attained, is illustrated in the accompanying drawings, in which—

Figure 1 is a view in elevation of one side of a cup embodying my invention. Fig. 2 is a view of the opposite side of the cup. Fig. 3 is a view in lengthwise section on 25 plane denoted by dotted line 3—3 of Fig. 1, the cup being shown as partially opened to illustrate its form when in use for drinking purposes, the thickness of the material being exaggerated. Fig. 4 is a view in section on 30 plane denoted by dotted line 4—4 of Fig. 1, the cup having the same form as in Fig. 3 and the thickness of the material being exaggerated.

My invention appertains to the class of 35 sanitary drinking cups composed of paper or other thin material folded to provide a flat structure, but the back and front walls of which are separated, especially at the top, when required for drinking purposes. 40 Heretofore the lips or drink edges of the cups have been composed of a single piece of thin material, as paper, with insufficient rigidity to resist collapse from the weight of the contents, with a result that such contents are liable to be spilled upon the person using the cup, and this single thickness also presenting a sharp edge liable to cut the flesh. My improved cup is constructed to 45 overcome these objections and the lip or drinking edge is sufficiently stiff to resist the weight of the contents and prevent collapse, such cup being illustrated in the accompanying drawings, in which the numeral 5 indicates what I term the front flap of the 55 cup, this being the flap, the upper or drink-

ing edge of which is presented to the lips in drinking, and the numeral 6 denotes the back flap. These two flaps are preferably formed of a single piece of material folded at the bottom edge 7 and the back flap is 60 preferably cut away as at 8 to remove such part as would be liable to make contact with the nose of the person using the cup.

The back flap 6 is provided with longitudinal folded edges 9 adapted to be folded over the front flap 5 to secure the two flaps together and close the seam at the edges of 65 said flaps.

The upper edge of the front flap is provided with a reinforcing or stiffening piece 70 10 that may be constructed in any desired manner, in a preferred form and as shown herein this being overturned from the flap 5. In order to increase the rigidity of this stiffening piece 10, by preventing a creeping 75 movement crosswise of the cup, this stiffening piece at its ends is located underneath the folds 9 and securely fastened thereunder. In the preferred form of construction both 80 sides of the stiffening piece are provided with an adhesive at the points overlaid by the folds 9, so that the stiffening piece at this point is secured firmly against the outer surface of the front flap 5 and the folds 9 are securely held against the outer surface 85 of the stiffening piece. Preferably the entire under surface of the latter is provided with an adhesive so that it is securely fastened against the outer surface of the flap 5. In order to provide the greatest rigidity at 90 the point of greatest strain the lip 10 is gradually widened from its ends to the center, at which latter point the greatest pressure occurs.

A cup constructed as above described is 95 found to possess all of the requirements for the use to which the cup is intended to be put, and the upper or drinking edge is sufficiently rigid to satisfactorily fulfil all of the functions required of it. It is to be understood, however, that the cup need not be 100 constructed exactly as illustrated and described herein, but that any other construction within the scope of the appended claims will be considered as embodying the invention.

I claim—

1. A drinking cup consisting of a front and back flap, a stiffening piece overturned on the outside of one of said flaps at the 110

upper edge thereof and extending thereacross, and means overlapping each end of said stiffening piece to secure it in place.

2. A drinking cup including a front and back flap, lengthwise folds for securing said flaps together, and a stiffening piece secured to the drinking edge of the cup and with its ends underlying said flaps and secured in place thereby.

10 3. A drinking cup composed of a front and a back flap, lengthwise folds for securing said flaps together, and a stiffening piece overturned on the outside of the drinking edge of said cup and extending underneath said folds and provided with an adhesive on its opposite sides to secure it to the flap and to secure the lengthwise folds thereto.

15 4. A drinking cup consisting of a front

and back flap, a stiffening piece secured to the upper edge of one of said flaps and 20 gradually increasing in width from its ends to its center, and folds at the edges of the cup engaging said stiffening piece to secure it in place.

25 5. A drinking cup including a front flap and a back flap, the latter being folded lengthwise at its edges onto the front face of the front flap, and a stiffening piece folded over from the upper edge of the front flap and having its ends underlying and secured by the folded edges of the back flap.

HENRY B. COOLEY.
